UNITED STATES PATENT OFFICE

2,382,329

BASEBALL GAME

Donald H. Munro, Toronto, Ontario, Canada

Application June 23, 1943, Serial No. 491,890

1 Claim. (Cl. 273—129)

My invention relates to parlor games and has for its object the provision of an interesting and amusing game simulative of national baseball and containing its characteristic features of play in a diversionary form.

The invention comprehends a board having a playing surface provided with two planar surfaces sloping downwardly from the mid-section thereof toward playing ends for the operators.

Upon the playing surface is delineated a baseball diamond upon which the movements of the team at bat may be pegged. A marble serves as the ball and is shot toward the catcher's box by a projecting device in conjunction with a locating guideway.

The catcher's box is defined by a pocket having a forwardly disposed flicking device representing a man at bat so that an operator may actuate the same with the intent of striking the ball. The flicking device has a swingable arm representing a bat, and skill and judgment is required for the operation of this swingable arm by its actuating means in order to hit the ball as it reaches the base-plate; otherwise it passes into the pocket and a strike is recorded against the operator.

Upon the playing surface is an arrangement of devices for catching the ball and representing the field men. Certain of the catching devices face the batman to act as the outfields and are located on the planar surface which inclines toward the remote end of the field so that should the ball be struck with only sufficient force to drive it to the crest, it will gravitate toward these catching devices. The others face away from the batman and are located on the adjoining planar surface so as to serve for the infielders or short stops.

At the head of the playing field is a transverse series of pockets into which the ball will gravitate from the adjacent inclined surface. These are used to indicate a "ball," foul strike and a caught foul ball. At the remote end of the playing field is a similar series of pockets for denoting bases made on a hit.

The game may be played by two or more players and its novel construction and arrangement will be more clearly understood by reference to the accompanying drawing in which:

Fig. 1 is a top elevation plan of the game in which a ball is shown in the pitcher's guideway ready for play.

Fig. 2 is a longitudinal section taken on line 2—2 of Fig. 1.

Fig. 3 is a bottom plan view of the board showing parts of the end walls broken away to indicate

more clearly the handle pieces of the several control mechanisms.

Fig. 4 is a perspective view of the fragmentary part of the head end of the board.

Fig. 5 is a sectional detail of one of the catching devices taken on line 5—5 of Fig. 1.

Like numerals of reference indicate corresponding parts in each of the figures throughout the drawing of the invention.

The drawing illustrates the preferred form of the invention which comprises an elongated game board A having a head end B and a remote end C, between which is a playing surface D bounded by edge walls E. The playing surface slopes downwardly from the mid-section F toward the ends and has delineated thereon, as by colour, a playing field including a baseball diamond G, the home plate of which is located adjacent to the head end, and the first and second bases are located upon the inclined surface 10 that slopes toward this end. Desirably the diamond has a line 11 extending between the home plate and the pitcher box 12.

At the pitcher's box is a device for projecting the ball 13 along the line 11 toward the home plate. A spherical metallic element is desirably used as a ball. The projecting device comprises a metal rod 14 swingably attached as at 15 to the underside of the board and projecting through a slot 16 therein for oscillatory movement in a plane longitudinally thereof.

The upwardly projecting end of the rod is fitted with a peg 17 representing the pitcher and the journalled part 15 has an arm 18 attached by a link rod 19 to a pull-handle 19' slidably mounted at the remote end C of the board for manipulation by a player. The rod 14 is normally retained at a rearwardly inclined angle by a spring 20 so that when the handle is pulled it will cause the peg to strike the ball to propel it forwardly; thus simulating a pitcher throwing the ball.

At the front of the peg 17 is a locating guideway in which the ball is placed so that it may be positioned for its propulsion toward the home plate. The guideway is composed of a pair of diverging rails 21 having their near ends suitably spaced apart to contain the ball and yet allow the peg 17 to strike it. Each rail is a wire rod member of U-shape formation invertedly arranged with its legs embedded in the board and having its bight or top pieces extending parallel to the playing surface at an elevation slightly greater than the semi-diameter of the ball so that the ball will fit partly thereunder to preclude its rebounding out or over the guideway which also

serves as a catching device for the pitcher, as will be later more fully explained.

At the head end B and open to the playing field is a pocket 22 constituting a catcher's box or cage, of which the mouth or entrance contains the home plate. The pocket is formed by the members 23 and the end wall of the board. A flicking device 24 is disposed at the mouth of the pocket 22 to represent the batter holding a bat for swinging over the base plate as in the real game. This flicking device is comprised of a peg or man 25 mounted on a wire rod 26 swingable about a vertical axis and having a lateral arm portion 27 representing the bat and continued beneath the board to provide a lever 28. The lever is connected by a link rod 29 to a pull handle 30 and spring urged as at 31 to retain it at an angle suitable for swinging forward to hit a "pitched" ball.

Upon the inclined section of the playing field adjoining the head end B there is provided two catching devices 32 which serve as infielders or short stop men, and upon the other inclined section thereof there is provided a suitable number of distributed catching devices 33 which serve for the outfielders.

The catching devices 32 and 33 are similar in construction to the guideway aforesaid comprised of the rails 21, and serve to catch and retain the ball. The catching devices 32 are open to a ball travelling toward the head end B, whereas the catching devices 33 are open to a ball travelling toward the remote end C. Deflectors, as at 35, may, if so desired, be used on the playing field for changing the course of the ball.

At one side of the catcher's box or cage is an inwardly sloping wall 36 having an edge face from which projects a tapering divisional element 37 forming pockets receptive to the ball, one of which bears the legend "Foul strike" and the other the legend "Ball." At the other side is a similar wall 38 having two divisional elements 39 bearing the legends "Ball," "Foul ball out" and "Foul strike." Similarly at the remote end C there is an inwardly sloping wall 40 having a series of divisional elements as at 41 composing pockets, of which the middle one is marked "Home run" and those on either side are marked "3 bases," "2 bases" and "1 base" to denote runs.

To play the game, the ball is placed upon the rails 21 of the pitcher's box, as shown in Fig. 1, and the projecting device thereat is actuated by the handle 19' to cause the man 17 to strike the ball, which propels it along the line 11 toward the base plate. As the ball is thus put into play by an operator at the remote end C of the board,

the handle 30 at the head end is manipulated by another operator representing the team at bat in order to actuate the flicking device 24 so that it will hit the ball. Should the bat 27 be swung 5 too quickly or too slowly the ball will pass between its free end and the adjacent member 23 of the catcher's box: a strike is called and the ball is caught in the pocket 22. A record of strikes 10 may be conveniently kept by a peg which may be placed in either of the two holes 42 in an edge wall of the board. The guideway at the pitcher's box acts as a catching device and should the ball be hit and driven into it, the ball will be retained 15 therein as if the pitcher had caught it. Therefore the batter is out and this catching device is marked accordingly. The batter is also out if the ball is caught in any of the catching devices 33 denoting the outfielders or is caught by the devices 32 representing the infielders or short stops 20 and marked "Bunt". If the ball fails to pass over the crest of the playing field it will gravitate toward the head end and enter one of the pockets 25 thereat, provided it is not caught by either of the devices 32. In the event of its rolling to the remote end of the board it will enter one of the pockets thereat signifying the bases made on a hit, which are then indicated on the diamond by inserting a peg 43 in a hole, as at 43', in the appropriate base. The runs for either team are 30 kept by pegging them as by the provision of holes 44 in an edge wall. A record of "Balls" is similarly pegged, for which purpose holes 45 are supplied.

The construction and operation of the game 35 will be clearly evident from the preceding description, and it will be manifest that such changes and modifications may be resorted to as come within the spirit of the invention.

What I claim is:

In a baseball game apparatus of the kind described comprising a board having a simulated 40 baseball diamond including a home plate and a pitcher's box; the improvement including means at the pitcher's box for projecting a ball toward the home plate, said means including an element adapted to be forwardly actuated to strike the ball, said element being of a less width than the ball, a pair of rails flanking said element and forwardly diverging therefrom, the inner ends of the rails being spaced apart to provide a passage to admit said element in its forward movement but prohibiting the ball from passing therethrough, and said rails being arranged on the board to also 45 serve as a catching device for the ball when it is rolled forwardly from the home plate.

DONALD H. MUNRO.
